(57) **CLAIM**

The ornamental design for an integrated lighting module, as shown and described.

DESCRIPTION

FIG. 1 illustrates a top perspective view of an integrated lighting module;

FIG. 2 illustrates a front view thereof;

FIG. 3 illustrates a rear view thereof;

FIG. 4 illustrates a left-side view thereof;

FIG. 5 illustrates a right-side view thereof;

FIG. 6 illustrates a top view thereof;

FIG. 7 illustrates a bottom view thereof; and,

FIG. 8 illustrates a bottom perspective view thereof.

The broken lines in the figures depict portions of the integrated lighting module that form no part of the claimed design.
